UNITED STATES PATENT OFFICE.

ZELIA NUTTALL, OF DRESDEN, GERMANY.

DESIGN FOR A TABLE.

SPECIFICATION forming part of Design No. 21,803, dated August 30, 1892.

Application filed August 5, 1892. Serial No. 442,284. Term of patent 3½ years.

To all whom it may concern:

Be it known that I, ZELIA NUTTALL, a citizen of the United States, now residing in Dresden, Germany, have invented and produced 5 a new and original Design for Tables, &c., of which the following is a specification, reference being had to the accompanying drawing.

The drawing represents in perspective a stool or low table embodying my design.

10 The leading features of my design consist in the peculiar angular contour given the legs or portions below the body constituting the sides and legs, as shown in said drawing.

15 A stool, table, or similar article embodying my design has a body or top portion A of rectangular appearance, with legs or supporting portions B below the same inclined outward somewhat, with the edges notched and

made into a series of alternate angular projections C and depressions D. Around the 20 edges of the body A and legs or supporting portions B is a plain edging F, which follows the line of the edges closely, and within the plain field inclosed by the edging on the supports or legs are circular or annular ornaments G, as shown.

Having thus described my invention, what I claim is—

25 The design for a table or stool, substantially as described, and shown in the accompanying 30 drawing.

ZELIA NUTTALL.
